UNITED STATES PATENT OFFICE.

CHARLES SCOTT, OF PHILADELPHIA, PENNSYLVANIA, ASSIGNOR TO THE
CHARLES SCOTT SPRING COMPANY, OF SAME PLACE.

CONFINING-BAND FOR SPRINGS.

SPECIFICATION forming part of Letters Patent No. 598,394, dated February 1, 1898.

Application filed July 14, 1897. Serial No. 644,561. (No model.)

To all whom it may concern:

Be it known that I, CHARLES SCOTT, a citizen of the United States, residing in Philadelphia, Pennsylvania, have invented certain Improvements in Confining-Bands for Springs, of which the following is a specification.

This invention relates to elliptical or half-elliptical laminated springs in which the leaves or plates of the spring are tightly confined at the center by means of a clamping-band pressed upon the same; and it consists of a provision whereby the leaves of the spring may have freer movement than usual and whereby greater and more uniform flexibility is effected, with decreased strain upon the spring under deflection, the liability of the leaves of the spring to break under strain being greatly lessened.

The invention consists in forming the clamping-band with a ribbed internal surface, whereby, although the band may retain the general strength and external shape of clamping-bands now in use, the internal binding-surface in contact with the leaves of the spring is of considerably less width than the width of the band, the confined area of the spring-leaves being, in fact, so limited that said leaves are permitted to deflect uniformly throughout their entire length.

In the accompanying drawings I have illustrated my invention as applied to a semi-elliptical spring, Figure 1 representing a side view of the spring with the improved band applied thereto. Fig. 2 is a view representing the under side of the spring and its confining-band. Fig. 3 is a sectional plan view on the line $x-x$, Fig. 1. Fig. 4 is a transverse section of the band on the line $y-y$, Fig. 2, showing portions of the spring-leaves in elevation; Fig. 5, a similar view showing the leaves as they appear when subjected to extreme strain; Fig. 6, a transverse section on the line $w-w$, Fig. 1; Figs. 7, 8, and 9, views illustrating various forms of spring-band embodying my invention; and Figs. 10 and 11 views illustrating the construction of and the objection to the ordinary form of clamping-band of the character to which my invention relates. Figs. 3 to 11, inclusive, are on a larger scale than Figs. 1 and 2.

In the manufacture of elliptical or semi-

elliptical springs it has been customary heretofore to firmly clamp together about the middle of their length the bundle of leaves forming the spring by means of a band of 55 metal of such width and thickness as to give it the necessary strength to insure a firm and rigid clamp. This band being pressed and shrunk into place adapts itself to and follows the curvature of the leaves of the spring, 60 as shown in Fig. 10 of the drawings. When the spring is deflected, therefore, the effect is that shown in Fig. 11, the portions of the leaves within the band being held perfectly rigid and retaining their original curvature, 65 while those portions of the leaves outside of the band are deflected, thus forming a bend in each leaf at the edges of the band and causing great strain at these points, which results in frequent breakage. My improve- 70 ment has been especially designed to overcome this defect, and said improvement consists, essentially, in providing the band with a ribbed internal surface, the rib being of considerably less width than the band, so that 75 while the said band contains the amount of material necessary for the desired strength and retains the external shape and dimensions of the ordinary band, so as to fit it to the ordinary spring attachments of cars, loco- 80 motives, or other vehicles, the internal clamping-surface of the band is much reduced and each leaf of the spring is free to be deflected throughout its entire length, as will be understood on reference to Figs. 4 and 5. 85

The internal ribbed surface of the band may be variously formed in accordance with my invention. Thus in Figs. 1 to 6 the rectangular band 1 has a central internal rib 2 extending around all four sides of the band, 90 the rib being of uniform width throughout and serving to confine only a limited portion of the center of each leaf of the spring.

In Figs. 7 and 8 multiple ribs are shown in place of a single rib, the rib 2^b (shown in Fig. 7) being double and the rib 2^c (shown in Fig. 8) being triple, and in some cases this form of multiple rib is to be preferred, the inner or bearing surface of each rib being either flat, as shown in Fig. 8, or rounded, as shown in Fig. 7.

While it is preferable to extend the internal

rib completely around the internal surface of the band, a rib extending along but two adjoining sides of the band may, if desired, be used, as shown, for instance, at 2^d in Fig. 9, 5 no material pressure being exerted upon the leaves of the spring throughout any portion of the opposing sides of the band except those directly opposite the rib, so that the leaves will have substantially the same freedom of 10 movement as though the rib extended completely around the band.

Having thus described my invention, I claim and desire to secure by Letters Patent—

15 1. A leaf-spring consisting of a series of leaves or plates confined together by a clamping-band ribbed internally on adjoining sides, the rib being of less width than the band whereby the leaves or plates of the spring are

confined throughout a less area than that of 20 the band.

2. A leaf-spring consisting of a series of leaves or plates, confined together by a clamping-band having an internally-projecting rib extending around the four sides of the band 25 and of less width than the band.

3. A leaf-spring consisting of a series of leaves or plates confined together by a clamping-band having on adjoining sides a rib of uniform width throughout and less in width 30 than the band.

In testimony whereof I have signed my name to this specification in the presence of two subscribing witnesses.

CHARLES SCOTT.
